UNITED STATES PATENT OFFICE.

MICHAEL RUDY, OF ROCHESTER, NEW YORK.

DESIGN FOR A TABLE-CASTER.

46,033.

Specification for Design. Patented June 30, 1914.

Application filed April 18, 1914. Serial No. 832,978. Term of patent 7 years.

To all whom it may concern:

Be it known that I, MICHAEL RUDY, a citizen of the United States, and residing at Rochester, in the county of Monroe and State of New York, have invented a new, original, and ornamental Design for Table-Casters, of which the following is a specification, reference being had to the accompanying drawing, forming part thereof.

Figure 1 is a perspective view of the table

caster; and Fig. 2 is a top plan view showing my design.

I claim:

The ornamental design for a table caster as shown.

MICHAEL RUDY.

Witnesses:

H. H. SIMMS,
ADA M. WHITMORE.
